(57) **CLAIM**

The ornamental design for a multi-cushion patient interface, as shown and described.

DESCRIPTION

FIG. 1 is a front perspective view of a multi-cushion patient interface showing our new design;

FIG. 2 is a front elevational view thereof;

FIG. 3 is a rear perspective view thereof;

FIG. 4 is a top plan view thereof;

FIG. 5 is a bottom plan view thereof;

FIG. 6 is a left side elevational view thereof; and,

FIG. 7 is a right side elevational view.

The portions drawn in broken lines are shown for illustrative purposes only and form no part of the claimed design.
